(57) CLAIM

The ornamental design for a filter box, as shown and described.

DESCRIPTION

FIG. 1 is a front perspective view showing our new design;
FIG. 2 is a front view thereof;
FIG. 3 is a top view thereof;
FIG. 4 is a bottom view thereof;
FIG. 5 is a back view thereof;
FIG. 6 is a right side view thereof;
FIG. 7 is a left side view thereof; and,
FIG. 8 is an enlarged perspective view of the section in FIG. 1.

The broken lines in the drawings depict portions of the filter box that form no part of the claimed design.
